AUTOMATIC LOCK SLIDER FOR SLIDE FASTENERS

Madison D. Pickens, Meadville, Pa., assignor to
Talon, Inc., a corporation of Pennsylvania

Application May 13, 1940, Serial No. 334,772

12 Claims. (Cl. 24—205.5)

This invention relates to slide fasteners and, in particular, to the provision of new and improved automatic lock sliders therefor.

It is an object of this invention to provide a new and improved lock slider construction which is thin and compact; wherein all projections such as pull tabs and supporting lugs are obviated; wherein the exterior slider surfaces are smooth, continuous, and uninterrupted; and wherein a substantially "streamline" appearance is achieved.

It is a further object of this invention to provide such a slider construction embodying new and improved lock actuating means, recessed in the slider body and normally flush therewith and which may be readily and conveniently manipulated, in various ways, for bringing the slider parts to unlocked position from their normal, locking position.

It is a further object of this invention to provide such a slider construction embodying a slider body which is so shaped as to react with underlying objects and materials to guide itself in the plane of the fastener.

It is a further object of this invention to provide such a slider body which is particularly adapted to facilitate manual engagement and actuation of a plate-like lock actuating member which is flush with the slider body.

It is a further object of this invention to provide such a new and improved automatic lock slider of simple, cheap and durable construction, readily and conveniently manufactured by any of the known methods of manufacture, either from metal or from non-metallic plastic materials, the component parts of which may be assembled with utmost facility.

These and other objects and advantages of the invention will appear from the following description taken in conjunction with the accompanying drawing which forms a part thereof, and will be pointed out in the appended claims.

In the drawing:

Fig. 1 is a perspective view showing a slide fastener slider, according to this invention, applied to an illustrative slide fastener, of which a fragmentary showing is made;

Fig. 2 is a longitudinal central section of the slider shown in Fig. 1, with the slider parts in normal, locking position;

Fig. 3 is a view similar to Fig. 2, but showing the slider parts in unlocked position, the lock actuating member being tilted in one direction for unlocking the slider;

Fig. 4 is a view similar to Fig. 3 and likewise

showing the slider parts in unlocked position, the lock actuating member being moved slidably in one direction longitudinally of the slider, for unlocking the slider;

5 Fig. 5 is a fragmentary transverse section taken substantially on the line 5—5 of Fig. 2; and

Fig. 6 is a transverse section taken substantially on the line 6—6 of Fig. 2.

In automatic lock sliders of the prior art, the lock actuating means generally constituted manually engageable pull tabs or other projections or protuberances loosely connected to the slider body, projecting substantially therefrom, and generally requiring protruding supporting lugs and requiring a substantial amount of relative movement between themselves and the slider body for unlocking the slider, by manually withdrawing the locking means from locking position.

These constructions were bulky, complicated and unsightly and the incorporation therein of effective locking means was accompanied, necessarily, by the disadvantages of substantial slider thickness and bulk, of expensive complicated construction, difficulty of assembly, extreme unsightliness and marked tendency toward catching of the pull tabs or other protuberances in clothing or other foreign materials, with which they came in contact in use.

According to the principles of this invention, 30 all of the above disadvantages of prior art constructions are totally obviated by elimination of pull tabs and pull tab supporting lugs from the slider construction of this invention, by the provision of a lock actuating member of plate-like form which is supported in a recess in the front wing of the slider in such manner that it is flush with the exterior surface of the front wing in the normal, locking position of the slider parts and which is movable, either slidably, longitudinally of the slider body, tilttable about either end, or movable bodily outwardly, such movement effectively and conveniently unlocking the slider by withdrawing the locking means thereof from its normal, locking position.

45 The slider in its preferred form comprises but three parts, namely, the slider body, a resilient locking member recessed in the slider body, and a lock actuating member operatively connected with the locking member in such manner as to be secured to the slider body by reason of its connection with the locking member. All of these parts are so compactly arranged as to provide a thin automatic lock slider having substantially smooth, uninterrupted exterior surfaces and presenting a "streamline" appearance.

Referring to the drawing in detail, the illustrative slide fastener shown in Fig. 1 comprises a pair of connected stringers and a slider slidable thereon for progressively engaging and disengaging the interlocking fastener members of the stringers for opening and closing the fastener. Each stringer comprises a stringer tape 18 having a reinforced edge 11 upon which reinforced edge 11 is secured a row of predeterminedly spaced interlocking fastener members 12. The reinforced edges 11 of the stringer tapes 18 are secured together adjacent the lower end of the rows of interlocking fastener members 12 by a conventional bottom stop 14.

The slider is generally designated 15 and is normally locked against movement longitudinally of the stringers, but may be manually unlocked by manipulation of the lock actuating member 32 which is of plate-like form and normally, when the slider 15 is locked, flush with the front surface of the slider, as shown in Figs. 2, 5 and 6. The lock actuating member 32 is tiltable, as shown in Figs. 1 and 3; longitudinally slidable, as shown in Fig. 4; or bodily movable outwardly of the slider (away from the plane of the fastener) for unlocking the slider.

The slider body, as shown in Figs. 3 to 5, comprises a front wing member 16 and a rear wing member 17 provided with marginal side flanges 18, which wing members 16 and 17 are secured together in predetermined spaced relationship, at their upper ends by a neck or wedge member 19. The inclined side surfaces of the neck member or wedge member 19 between the front and rear wing members 16 and 17 cooperate with the inner surfaces of the marginal side flanges 18 to form between the front and rear wing members 16 and 17, an upwardly diverging substantially V-shaped fastener member guide channel 20 for guiding the interlocking fastener members 12 into and out of meshing engagement upon relative longitudinal movement between the slider 15 and the stringers of the fastener.

The front wing member 16 is provided with a longitudinal locking member receiving recess 21 which communicates with the fastener member guide channel 20 through a locking projection receiving opening or aperture 22 extended from the lower end of the locking member receiving recess 21 into the fastener member guide channel 20. Extending rearwardly from the upper end of the locking member receiving recess 21 is a deep, transverse recess 24 which receives the leg portion 29 of the locking member 25 which is anchored in the recess 24, as hereinafter most clearly described.

The locking member is generally designated 25 and is disposed longitudinally of the slider having its main portion 26 provided with an intermediate outwardly bent or upstruck loop portion 27 while the lower end thereof terminates in an upwardly bent portion forming locking projections 28, which are disposed in the above-described locking projection receiving opening or aperture 22 and which are projectible therethrough into the fastener member guide channel 20, as shown in Figs. 2 and 5.

The upper end of the locking member 25 is bent inwardly to form the leg portion 29 which is disposed substantially perpendicular to the main portion 26 of the locking member 25 and which is closely fitted into the above-described recess 24. The sides of the leg portion 29 are provided with saw-tooth notches 30, into which the material of the slider body is projected, as

shown in Fig. 6, rigidly to secure the leg portion 29 of the locking member 25 to the slider body 15. Where the slider body is formed of metal, this is achieved by upsetting the metal of the slider body adjacent the saw-tooth notches 30. Where the slider body is formed of non-metallic plastic material, the material adjacent the saw-tooth notches is softened, pressed into the notches 30, and then allowed to harden in order to secure the leg portion 29 of the lock member 25 rigidly to the slider body.

Overlying the locking member receiving recess 21 is a longitudinally open-ended channel 31 which provides a seat for the plate-like lock actuating member 32. The outer surface of the lock actuating member 32 is preferably so formed that, in the normal position of the parts, as shown in Figs. 2, 5 and 6, the outer surface thereof is completely complementary with the flush surfaces of the front wing member 16 at each side thereof in order that a completely uninterrupted, or continuous front slider surface is formed.

Extending inwardly from the inner surface of the lock actuating member 32, substantially midway of its length, is a pair of substantially L-shaped coupling members 33 having the end projections 34 thereof, which are substantially horizontal, facing one another and somewhat sharpened, as shown in Fig. 5. These coupling members in effect form a connecting loop for the lock actuating member to the locking member 25.

The sharpened end projections 34 of the coupling members 33 extend under the intermediate outwardly bent or upstruck loop portion 27, the undersurface of which forms a cam surface, whereby longitudinal sliding movement of the lock actuating member 32, as shown in Fig. 4, causes the lower or free end of the locking member 25 to move outwardly and thus causes withdrawal of the locking projections 28 outwardly from the fastener member guide channel 20 through the opening or aperture 22.

Because of the inherent resiliency of the coupling members 33, in order to assemble the slider, it is merely necessary, after separate formation of the slider body 15, the locking member 25, and the lock actuating member 32, to secure the leg portion 29 of the locking member 25 in the recess 24, as described above, then to apply outward pressure upon the end projections 34 to bring the locking member 25 to the position shown in Fig. 4, and while the locking member is held in this position, to force the lock actuating member 32 inwardly of the slider body. The resilient coupling members 33 are thus spread apart sufficiently to allow the end projections 34 thereof to snap over the upstruck loop portion or cam portion 27 of the locking member 25, thus securely to assemble the slider body 15, locking member 25 and lock actuating member 32 together.

As shown in Figs. 1 and 3, tilting movement of the lock actuating member 32, in either direction with respect to the slider body 15, causes the outer or free end of the locking member 25 to move outwardly of the slider and causes withdrawal of the locking projections 28 from the fastener member guide channel 20.

Likewise, as will be clearly understood from Fig. 4, longitudinal sliding movement of the lock actuating member 32, in either direction with respect to the slider body 15, will likewise cause the outer end of the locking member 25 to be lifted to withdraw the locking projections 28

through the opening or aperture 22 from the fastener member guiding channel 28.

In order to limit the longitudinal sliding movement of the plate-like lock actuating member 32, in either direction, a pair of lands, ridges, or other projections 36 may, optionally, be provided on the inner surfaces of the lock actuating member 32, as shown in Fig. 4. These lands or ridges are preferably so spaced as predeterminedly to limit the longitudinal movement of the plate-like lock actuating member 32 in either direction, thus limiting the stress which may be applied to the locking member 25 due to this movement for preventing damage to the locking member 25.

In order to facilitate manipulation of the plate-like lock actuating member 32, the slider body 15 is preferably provided, at each end of the above-described channel 31, with a pair of undercut recesses 36, as shown in Figs. 1 to 4 inclusive. A fingertip or finger nail may be readily inserted under either end of plate-like lock actuating member 32 in an undercut recess 36 to pry up that end of the lock actuating member 32, as shown in Figs. 1 and 3, or to move the lock actuating member 32 slidably longitudinally of the slider, as shown in Fig. 4. Likewise, finger tips or finger nails may be inserted, at the same time, in both of the undercut recesses 36, and the lock actuating member may be lifted outwardly bodily with respect to the slider body 15 to unlock the slider.

The inner, under, or back surface of the slider is so formed as to resist catching of the slider upon underlying bodies, objects or materials, this surface being smooth throughout and the upper end thereof being provided with an upwardly and outwardly inclined or beveled portion 37 forming in effect a guiding shoe, which tends, upon encountering an underlying object, to "climb" upon the object and cause the upper end of the slider to move outwardly. This causes the slider to guide itself in the plane of the fastener, irrespective of tilting force exerted upon the slider when the lower end of the lock actuating member 32 is lifted to tilt the actuating member 32, as shown in Fig. 3. The component of the tilting force exerted upon the slider body by lifting of the lower end of the lock actuating member 32 is thus offset, or cancelled, by the reverse component exerted by the upwardly and outwardly inclined portion or guiding shoe 37 of the rear wing of the slider whereby the slider will run free, in the plane of the fastener, when the lower end of the lock actuating member 32 is lifted to cause upward sliding movement of the slider for closing the fastener.

From the above description, it will clearly appear that I have provided a new and improved slider construction which may be readily and conveniently produced by any of the known methods of manufacture from any suitable materials and wherein the component parts may be assembled with utmost ease and facility.

It will further appear that this slider construction is completely "streamlined," being provided with smooth, uninterrupted exterior surfaces highly resistant to catching or fouling of the slider in clothing or other objects and particularly adapted to guide the slider in the plane of the fastener.

It will further appear that the component parts of the slider have been reduced to a minimum and that the lock actuating means, which is normally flush with the exterior surfaces of

the slider, may be operated conveniently in various ways, effectively to unlock the slider, free access to the lock actuating means being provided by undercut recesses underlying the ends of the lock actuating member.

It is, of course, to be understood that the above description is merely illustrative and in nowise limiting and that I desire to comprehend with my invention such modifications as are included within the scope of the appended claims.

Having thus fully described my invention, what I claim as new and desire to secure by Letters Patent is:

1. In a slider for slide fasteners, a slider body having locking means enclosed therein, and a lock actuating member operatively connected with said locking means and secured to one side of said slider body, said lock actuating member being movable with respect to said slider body, slidably in opposite directions and tiltingly about opposite end portions for operating said locking means.

2. In a slider for slide fasteners, a slider body having normally operative locking means enclosed therein, said slider body having a channel extending inwardly from one side thereof and overlying said locking means, and a lock actuating member in said channel normally flush with the adjacent surfaces of said slider body and slidably and tiltably in opposite directions therein, said lock actuating member being operatively connected with said locking means and retained in said channel by said connection, and said lock actuating member rendering said locking means inoperative upon movement of said lock actuating member bodily outwardly, tiltingly or slidably in either direction with respect to said channel.

3. In a slider for slide fasteners, a slider body having locking means enclosed therein, and a manually engageable lock actuating member movably supported at one side of said slider with its outer surface normally flush with the adjacent surfaces of said slider body, said slider body having undercut recesses underlying the ends of said lock actuating member for facilitating manual access thereto.

4. In a slider for slide fasteners, a slider body having a fastener member guide channel therein and means associated therewith and operable manually from the front of the slider for moving said slider, the rear surface of said slider body having an upwardly and outwardly inclined surface at its upper end forming a guiding shoe resisting tilting of the upper end of said slider inwardly upon upward movement of said slider for guiding said slider substantially in the plane of fastener members in said fastener member guide channel.

5. In a slider for slide fasteners, a slider body, normally operative locking means enclosed in said slider body, said slider body having a channel extending inwardly from the outer side thereof, and a manually engageable lock actuating member in said channel having its outer surface normally flush with the outer surface of said slider body, said lock actuating member being bodily movable outwardly of said channel, slidably in said channel in either direction or tiltingly in opposite directions therein, said lock actuating member being operatively connected with said locking means and rendering said locking means inoperative upon such movement of said lock actuating member in said channel, said slider body having undercut recesses commun-

cating with the ends of said channel and underlying the ends of said lock actuating member for facilitating manual access thereto, and the inner side of said slider body having an upwardly and outwardly inclined surface at its upper end forming a guiding shoe resisting inward tilting of the upper end of said slider upon upward movement thereof for closing a slide fastener.

6. In an automatic lock slider for slide fasteners, a slider body having therein a fastener member guiding channel, a locking member recessed in said slider body and having thereon a locking projection normally projected in said guide channel for locking engagement with fastener members therein, one side of said slider body having an elongated recessed channel coextensive therewith and a manually engageable lock actuating member operatively connected with said locking member and having its outer surface substantially flush with surfaces of said slider body adjacent said elongated recessed channel, said lock actuating member being movable bodily outwardly of said channel, slidably in either direction in said channel and tiltably in said channel in either direction for withdrawing said locking projection from said guide channel to unlock said slider.

7. In an automatic lock slider for slide fasteners, a slider body having therein a fastener member guide channel, a locking member receiving recess extending inwardly from one side of said slider body, a locking member in said locking member receiving recess comprising a yieldable member fixed at one end to said slider body and having an inwardly directed locking projection at its free end normally projecting into said guide channel, said locking member having an upstruck loop portion between its ends, and a manually engageable lock actuating member overlying said locking member receiving recess and having its outer surfaces substantially complementary with adjacent surfaces of said slider body, and means operatively connecting said lock actuating member with said locking member, said last named means cooperating with said loop portion to cause withdrawal of said locking projection from said fastener member guide channel upon manual movement of said lock actuating member with respect to said slider body.

8. In an automatic lock slider for slide fasteners, a slider body having therein a fastener member guide channel, a locking member receiving recess extending inwardly from one side of said slider body, and an elongated lock actuating member supporting channel overlying said locking member receiving recess, a locking member in said locking member receiving recess comprising an elongated resilient member fixed at one end to said slider body and having an inwardly directed locking projection at its free end normally projecting into said guide channel, said locking member having an upstruck loop portion intermediate its ends, a manually engageable plate-like lock actuating member in said lock actuating member supporting channel overlying said locking member receiving recess and having its outer surfaces normally substantially flush with adjacent surfaces of said slider body, and coupling means operatively connecting said lock actuating member with said locking member while retaining said lock actuating member in said lock actuating member supporting channel comprising a connector loop secured to the inner side of said lock actuating member and extend-

ing under the upstruck loop portion of said locking member, said coupling means cooperating with said upstruck loop portion to cause withdrawal of said locking projection from said fastener member guide channel by lifting said locking member outwardly of said slider body upon manual movement of said lock actuating member with respect to said lock actuating member supporting channel.

9. In an automatic lock slider for slide fasteners, a slider body having therein a fastener member guide channel, an elongated locking member receiving recess extending inwardly from one side of said slider body and spaced from said guide channel, and a locking member leg receiving recess extending inwardly from one end of said locking member receiving recess, a locking member in said locking member receiving recess comprising an elongated yieldable member having an inwardly directed locking projection at one end normally projecting into said guide channel, an inwardly extending leg at its other end fixed in said leg receiving recess, and having an upstruck loop portion between said locking projection and said leg, and a manually engageable plate-like lock actuating member overlying said locking member receiving recess and having its outer surfaces normally substantially flush with adjacent surfaces of said slider body, and connecting means operatively connecting said lock actuating member with said locking member while retaining said lock actuating member and said slider body together, said connecting means including a loop extending inwardly in said locking member receiving recess from the inner side of said lock actuating member and extending under the upstruck loop portion of said locking member, said coupling means cooperating with said loop portion to cause withdrawal of said locking projection from said fastener member guide channel by lifting said locking member outwardly of said slider body upon manual movement of said lock actuating member either bodily outwardly, tiltably, or slidably in either direction with respect to said slider body.

10. The structure defined in claim 9, said leg of said locking member having at least one saw-toothed notch therein, and the material of said slider body extending therein for anchoring said leg to said slider body.

11. In an automatic lock slider for slide fasteners, a slider body having therein a fastener member guide channel, a longitudinal locking member receiving recess extending inwardly from one side of said slider body and spaced from said guide channel, a locking projection receiving aperture extending between one end of said locking member receiving recess and said guide channel, a locking member leg receiving recess extending inwardly from the other end of said locking member receiving recess, and an elongated lock actuating member supporting channel overlying said locking member receiving recess, an elongated yieldable locking member in said locking member receiving recess having an inwardly directed locking projection at one end disposed in said locking projection receiving aperture and normally projecting into said guide channel, an inwardly extending leg at its other end fixed in said leg receiving recess, and having an upstruck loop portion between said locking projection and said leg, a manually engageable plate-like lock actuating member in said lock actuating member supporting channel overlying said locking member receiving recess and having its outer surfaces

normally substantially flush with adjacent surfaces of said slider body, and connecting means operatively connecting said lock actuating member with said locking member while retaining said lock actuating member in said lock actuating member supporting channel, said connecting means comprising a pair of complementary coupling members secured to the inner side of said lock actuating member and extending under the upstruck loop portion of said locking member, said coupling members cooperating with said loop portion to cause withdrawal of said locking projection from said fastener member guide channel by lifting said locking member outwardly of said slider body upon manual movement of said lock actuating member either bodily outwardly, tilt-

ably, or slidably in either direction with respect to said lock actuating member supporting channel, said coupling members being yieldable and snapping over the upstruck loop portion of said locking member upon application of force inwardly upon said lock actuating member for ease of assemblage of said lock actuating member to said locking member and said slider body.

12. A slider for slide fasteners including a slider body having therein a fastener member guide channel, said slider body being provided, at one end at least, with an undercut finger tip accommodating recess facilitating manual engagement of said slider body.

15

MADISON D. PICKENS.
